UNITED STATES PATENT OFFICE.

ARTHUR W. CUSHMAN, OF WINNETKA, ILLINOIS, ASSIGNOR TO ALLIED PACKERS, INC., OF CHICAGO, ILLINOIS, A CORPORATION OF DELAWARE.

METHOD OF PREPARING SMOKED JOINT MEATS.

No Drawing.

Application filed June 30, 1926. Serial No. 119,754.

The present invention has to do with the smoking of hams, shoulders, and other joint meats, and is particularly concerned with the effect of the smoking operation on the appearance and flavor of the same.

The ordinary method of curing a ham consists in first pickling the ham and then hanging it uncovered in a smoke house where it is subjected to smoke and heat for the necessary length of time. As a result of such treatment, the ham is properly cured, but is left in a rather unsightly condition owing to the presence of fissures formed in and about the butt of the same by the action of the smoke and heat.

A method of curing which leaves the ham in much better condition is known as the "stockinet" process and is covered in Patent No. 1,122,715. In practicing that method, the ham after being pickled, is placed in a jacket of elastic material, and is smoked while suspended in the jacket. The method is quite efficacious in rounding up the butt and preventing the formation of fissures in the same, but the jacket interferes to a certain extent with the action of the smoke, and receives part of the preservative coating which would be more effective if deposited by the smoke on the surface of the ham.

The object of the invention is to provide an improved method of preparing smoked hams which is simple and inexpensive to practice, which permits the smoke to come into direct contact with the ham, which rounds up the butt, and which leaves the ham in a jacket which is clean and may be either removed and reused or else retained as a covering for the ham when sold.

The method of the invention consists in pickling and smoking the ham in the ordinary way, then encasing the ham, while still hot and plastic as a result of the smoking operation, in a jacket of either elastic or non-elastic material, and then suspending the ham in the jacket and permitting it to cool and harden under the shaping pressure exerted thereagainst by the jacket.

A ham which has been treated in accordance with the invention has not only the well-shaped appearance of a ham prepared under the "stockinet" process, but also a deeper and richer color, and is more thor-

oughly covered by the preservative coating produced thereon by the smoke. Furthermore, the jacket used on the ham during the shaping of the same following the smoking operation is not soiled by the smoke, and may be removed, easily washed, and reused on another ham, or else may be retained on the ham as a covering for the same when sold. If the jacket is to be left on the ham when sold and it is desired that the jacket have a smoked color, the ham, after undergoing the treatment of the invention, may be resmoked for a short time with the jacket on.

The method of the invention is not restricted in its application to joint meats with the bone therein, or even to joint meats with or without the bone, as it may also be used to advantage with other meats such as boneless cuts.

I claim:

1. A method of preparing smoked meats, which consists in smoking the meat while uncovered, then encasing the meat while still hot and plastic as a result of the smoking operation in a jacket of flexible material, and then suspending the meat in the jacket and permitting it to cool and harden under the shaping pressure exerted thereagainst by the jacket.

2. A method of preparing smoked joint meats, which consists in smoking the joint while uncovered, then encasing the joint while still hot and plastic as a result of the smoking operation in a jacket of flexible material, and then suspending the joint in the jacket and permitting it to cool and harden under the shaping pressure exerted thereagainst by the jacket.

3. A method of preparing hams with or without the bone therein, which consists in first pickling the ham, then smoking the ham while uncovered, then encasing the ham while still hot and plastic as a result of the smoking operation in a jacket of flexible material, and then suspending the ham in the jacket and permitting it to cool and harden under the shaping pressure exerted thereagainst by the jacket.

4. A method of preparing whole hams, which consists in first pickling the ham, then smoking the ham while uncovered, then encasing the ham while still hot and plastic

as a result of the smoking operation in a jacket of flexible material, and then suspending the ham in the jacket and permitting it to cool and harden under the shaping pressure exerted thereagainst by the jacket.

5. A method of preparing whole hams, which consists in first pickling the ham, then smoking the ham while uncovered, then encasing the ham while still hot and plastic

as a result of the smoking operation in a 10 jacket of flexible material, then again smoking the ham with the jacket on, and then permitting the ham to cool and harden in the jacket under the shaping pressure exerted by the jacket on the ham.

15 In testimony whereof, I have hereunto subscribed my name.

ARTHUR W. CUSHMAN.
